UNITED STATES PATENT OFFICE.

ISAAC A. SCHWARZ, OF PHILADELPHIA, PENNSYLVANIA, ASSIGNOR TO
AUGUSTUS A. LAZARUS, ISAAC A. SCHWARZ, AND BENJAMIN LIPPER,
OF SAME PLACE.

DESIGN FOR TRIMMING.

SPECIFICATION forming part of Design No. 21,646, dated June 21, 1892.

Application filed May 21, 1892. Serial No. 433,915. Term of patent 3½ years.

To all whom it may concern:

Be it known that I, ISAAC A. SCHWARZ, a citizen of the United States, and a resident of Philadelphia, Pennsylvania, have invented a new and original Design for Dress-Trimming, of which the following is a specification.

My design is fully shown in the accompanying drawing, which represents a face view of a piece of the trimming.

10 The design comprises the central tape-like band or ribbon *a*, close to the edges of which are narrow bands *b*, and projecting from each edge of the central band are arched cords *f*, those at one edge of the band being in line 15 with the spaces between the arched cords at the opposite edge of the band. A cord *g* is carried back and forth in waved lines across

the central band *a* and forms loops within the arched cords at the opposite edges of said band.

Outer bands *d* connect the various projecting loops; but these outer bands do not form an essential part of the design.

I claim—

The design for dress-trimming, substantially as described, and as shown in the accompanying drawing.

In testimony whereof I have signed my name to this specification in the presence of two subscribing witnesses.

ISAAC A. SCHWARZ.
